UNITED STATES PATENT OFFICE.

STANHOPE BOAL, OF PIQUA, OHIO.

DESIGN FOR A STOVE OR RANGE.

SPECIFICATION forming part of Design No. 30,188, dated February 14, 1899.

Application filed January 12, 1899. Serial No. 701,994. Term of patent 7 years.

To all whom it may concern:

Be it known that I, STANHOPE BOAL, residing at Piqua, in the county of Miami and State of Ohio, have invented and produced a new and original Design for Stoves or Ranges, of which the following is a specification.

The object of my invention is to produce a new and original design comprising an elongated scrollwork as the chief feature of ornamentation applied to a stove or range.

The figure represents a perspective view of a stove with my design applied.

It will be observed that the characteristic scrolls of the different parts of a stove or range correspond with each other in general appearance. Almost the entire surface of the stove sides is covered with this elongated scroll ornamentation, giving a harmonious and beautiful appearance. The general effect

produced is a series of elongated scrolls radiating from a center on the stove-door and reservoir-plate, and the same feature of ornamentation is applied to the base-plate and smaller stove parts as nearly as possible. This center on the oven-door is a name-plate bordered with a series of elongated scrolls partaking of the general features peculiar to this design.

Having described my invention, I claim—

The design for a stove or range as herein shown and described.

In testimony whereof I have hereunto set my hand.

STANHOPE BOAL.
